UNITED STATES PATENT OFFICE.

ANDREW W. JOHNSON, OF KANSAS CITY, MISSOURI.

SAFETY-BLADE HOLDER

1,258,778.

Specification of Letters Patent. Patented Mar. 12, 1918.

Application filed March 6, 1917. Serial No. 152,783.

To all whom it may concern:

Be it known that I, ANDREW W. JOHNSON, a citizen of the United States, residing at Kansas City, in the county of Jackson and State of Missouri, have invented certain useful Improvements in Safety-Blade Holders, of which the following is a specification, reference being had therein to the accompanying drawing.

10 The present invention has reference generally to improvements in that class of inventions known as cutlery and more particularly relates to an improved safety blade holder.

15 As the primary aim and object the present invention contemplates the provision of novel antifriction means mounted on the body of the holder whereby the holder may be manipulated with more ease and rapidity 20 when being moved back and forth across the surface of a strop as a blade is being sharpened thus facilitating the sharpening of the blade without injuring the strop.

More particularly, the invention includes 25 the provision of novel means for mounting a pair of anti-friction rollers on opposite sides of the body adjacent the blade clamping means.

30 Among the other aims and objects of the invention may be recited the provision of a device of the character mentioned with a view to compactness, and in which the number of parts are few, the construction simple, the cost of production low and the efficiency 35 high.

Other improvements and novel details in the construction and arrangement of the various parts of the apparatus will be brought out more in detail in the description 40 to follow, which for a clear understanding of the invention, should be considered in connection with the accompanying drawings forming a part hereof, and wherein is disclosed for the purpose of illustration a 45 convenient and satisfactory embodiment of the invention. It is to be noted in this connection that minor changes in the construction and arrangement of parts may be made without departing from the spirit of the invention or the principle of operation of the 50 various parts.

The preferred embodiment of the present invention is clearly illustrated in the accompanying drawings, in which:

55 Figure 1 is a perspective view of the invention.

Fig. 2 is an enlarged fragmentary longitudinal section through the body the blade clamping means being shown in elevation.

Fig. 3 is a transverse section taken on line 3—3 of Fig. 2.

Fig. 4 is a longitudinal section taken on line 4—4 of Fig. 3 in the direction in which the arrows point.

Fig. 5 is a transverse section taken on line 5—5 of Fig. 2 in the direction in which the arrows point.

Similar characters of reference are employed in all of the above described views, to indicate corresponding parts.

Referring now, more particularly, to the accompanying drawings, there is provided a body 1 tubular in cross section and knurled exteriorly near one end as indicated at 2 to form a handle while the opposite end constitutes a blade holding portion and is closed at the outer end and formed with a transverse partition 2' near the handle portion. The blade holding portion is also formed with a longitudinal slot 3 and is further formed interiorly with spaced parallel webs 3' which are integral with the opposite sides of the slot and opposed points on the inner surface of the blade holding portion as clearly shown in Fig. 5. The ends of the webs 3' are joined with the partition 2' and the closed end on opposite sides of the recesses 4' therein.

With a view toward providing suitable blade clamping means on the body there is employed a pair of complementary resilient blade receiving and clamping jaws 4 on the inner ends of which are formed ears 5 while a transversely extending pivot pin 6 serves to pivotally engage the ears and consequently pivotally mount the jaws so that they may be swung through the slot and recesses and between the webs subsequent to receiving a razor blade 7. Finger engaging portions 8 extend longitudinally from the outer ends of the jaws 4 and project beyond the free end of the blade so as to be readily engaged when it is desired to swing the jaws from engagement with the slots, etc.

As intimated, improved anti-friction means have been provided for facilitating the sharpening of the blade 7 without injuring a strop. In accomplishing this, the blade holding portion of the body at points 110 parallel with the medial line of each web on the outer surface is formed with opposed

elongated apertures 9. Ears 10 are formed integral with the inner surface of the tubular portion of the body or handle while improved anti-friction rollers 11 having trunnions 12 formed on the ends thereof are positioned within the apertures while the trunnions are rotatably mounted respectively in the outer closed end of the blade holding portion and in the ears so as to dispose the outer surface of the rollers slightly beyond the outer surface of the body whereby when the handle is engaged and the holder manipulated in the usual manner for sharpening a blade the rollers will engage the strop and slide freely thereover without injuring the strop, thereby facilitating the sharpening of the blade 7.

It is believed in view of the foregoing description that a detailed description of the 20 operation of the invention is entirely unnecessary. Likewise it is believed that the advantages of the invention will be readily apparent.

As many changes could be made in the 25 above construction and many apparently widely different embodiments of this invention could be made without departing from the scope thereof, and it is intended that all matter contained in the above description 30 or shown in the accompanying drawings shall be interpreted as illustrative and not in a limited sense. It is also to be understood that the language used in the following claim is intended to cover all the generic 35 and specific features of the invention herein described and all statements of the scope of the invention, which, as a matter of language might be said to fall therebetween.

Having thus fully described this invention, what is claimed as new and desired 40 to be secured by Letters-Patent, is:-

A blade holder of the character described including a tubular body one end of which constitutes a handle, the opposite end of the body constituting a blade holding portion 45 and being provided with a longitudinal slot while the outer end of the blade holding portion is closed and formed with a recess, a partition blade holding portion having a recess therein, spaced parallel webs integral 50 with the inner surface of the blade holding portion and joined at its opposite sides upon opposite sides of the slot and at opposed points with the inner surface of the blade holding portion and having the ends joined with the closed end and with the partition upon opposite sides of the recesses, the opposite sides of the blade holding portion at points parallel with the medial line of each web being formed with elongated 55 apertures, complementary resilient blade receiving and clamping jaws pivotally mounted in the body and swingable through the slot and recesses and between the webs, ears formed within the body adjacent the inner 60 ends of the apertures, anti-friction rollers, and trunnions formed on the respective ends of the rollers and journaled in the outer closed end and in the ears so as to slidably 65 mount the rollers within the apertures and 70 arrange the outer surfaces of the rollers slightly beyond the outer surface of the blade holding portion.

In testimony whereof, I affix my signature.

ANDREW W. JOHNSON
